(21) Appl. No.: **29/372,423**

CLAIM

(22) Filed: **Nov. 18, 2010**

The ornamental design for a cartridge for a medical rod cutter, as shown and described.

(51) **LOC (9) Cl.** **24-02**

DESCRIPTION

(52) **U.S. Cl.** **D24/146**

FIG. 1 is a front perspective view of a cartridge for a medical rod cutter showing my new design;

(58) **Field of Classification Search** D24/133,

FIG. 2 is a top perspective view thereof;

D24/137, 138, 143–149; 606/151, 157, 158,

FIG. 3 is a rear perspective view thereof;

606/167, 182, 176, 184, 205–208, 112–150

FIG. 4 is a right side elevation view thereof;

See application file for complete search history.

FIG. 5 is a left side elevation view thereof;

FIG. 6 is a top plan view thereof;

FIG. 7 is a bottom plan view thereof;

FIG. 8 is a left end elevation view thereof; and,

FIG. 9 is a right end elevation view thereof.

D24/137, 138, 143–149; 606/151, 157, 158,

The broken line showing of the cartridge for a medical rod cutter is for illustrative purposes only and forms no part of the claimed design.
